H. W. TOMPKINS

RADIO VARIABLE RHEOSTAT

Filed Aug. 2, 1922

By *Abundant, Jr.*
Attorney

UNITED STATES PATENT OFFICE.

HERMAN W. TOMPKINS, OF GREENSBURG, PENNSYLVANIA.

RADIO VARIABLE RHEOSTAT.

Application filed August 2, 1922. Serial No. 579,203.

To all whom it may concern:

Be it known that I, HERMAN W. TOMPKINS, a citizen of the United States, residing at Greensburg, in the county of Westmoreland and State of Pennsylvania, have invented certain new and useful Improvements in Radio Variable Rheostats; and I do hereby declare the following to be a full, clear, and exact description of the invention, such as will enable others skilled in the art to which it appertains to make and use the same.

The present invention has relation to radio apparatus and more particularly to a variable rheostat which is simple in its structure and arrangement of parts, whereby it may be readily assembled and economically constructed, and which is accessible for any required purpose.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a front view of a radio variable rheostat embodying the invention,

Figure 2 is a side view thereof,

Figure 3 is a horizontal section on the line 3—3 of Figure 2,

Figure 4 is a detail perspective view of the hub, and

Figure 5 is a view similar to Figure 2 showing a different arrangement.

Corresponding and like parts are referred to in the following description and designated in the several views of the drawings by like reference characters.

The numeral 1 designates a panel of a radio apparatus to which the rheostat is attached. 2 designates a metal base plate attached to the panel 1 by means of screws 3 or analogous fastening means. A hub 4 is mounted on the base plate 2 and pivoted thereto by means of a pin 5. The sides of the hub 4 are flat and parallel and the edge is broad and calibrated as indicated at 6 to indicate the resistance in circuit. A handle 7 pro-

jects outwardly from the edge of the hub 4 and provides convenient means for rotating the same. A blade 8 is attached to the hub 4 at a point diametrically opposite the handle 7 and projects from the hub in an opposite direction to the handle 7. The parts 7 and 8 may be secured to the hub 4 in any preferred way. The hub 4 and blade 8 are of metal so as to form a part of the circuit.

A semicircular support 9 of insulating material such as fibre, hard rubber or the like, is attached at its ends to the base plate 2 and is arranged concentric with the pivot 5 of the hub 4. A binding post 10 connects one end of the support 9 to the base plate 2 and a binding post 11 connects the opposite end of the support 9 to the other end of the base plate 2. The binding post 10 is in electric connection with the base plate 2, whereas the binding post 11 is electrically insulated from the base plate 2. The lead wires (not shown) are adapted to be connected to the binding posts 10 and 11. A resistance wire 12 is wound about the support 9 and its ends are connected to the respective binding posts 10 and 11. The outer end of the blade 8 is in electrical contact with the resistance wire 12 and its position determines the resistance in the circuit.

The lead wire connected to the binding post 10 is in electric connection with the resistance wire 12 and blade 8 and the lead wire connected to the binding post 11 is in electric connection with the resistance wire 12 only. Owing to the fact that an electric current tends to travel in the path of least resistance, it will be understood that the circuit is from binding post 10 through plate 2, hub 4, blade 8 and resistance wire 12 to binding post 11. The position of the blade 8 determines the length of resistance in the circuit and the same is indicated by the graduations 6 on the hub 4. When the parts are in place, the base plate 2, a portion of the hub 4, and the handle 7 appear on the front side of the panel, whereas the remaining parts are disposed upon the rear side of the panel and are hidden from view.

As shown in Figure 5, the base plate 2 may be arranged upon the inner or rear side of the panel, thereby obviating detachment therefrom of the support 9 and the resistance 12 when placing the parts in position

or removing them from the panel. Obviously any number of cooperating parts may be applied in gang to the one base plate.

What is claimed is:

- 5 1. A radio-variable rheostat comprising a metal base plate, a metal hub pivotally mounted upon the base plate and provided with calibrations, a semicircular resistance secured at opposite ends to the base plate
- 10 upon opposite sides of the hub and concentric therewith, one end of the resistance having electrical connection with the base plate, and the opposite end being electrically insulated therefrom, and a metal blade carried
- 15 by the hub and in electric connection with the resistance to bring more or less thereof into circuit.
- 20 2. A variable rheostat for radio apparatus comprising a base plate having a slot therein and adapted to be secured to a panel of a radio apparatus, a disk shaped hub member positioned in said slot and pivoted to said plate, a handle for rotating said hub member and positioned on the outer side of
- 25 said panel, an arcuate support of insulating

material secured at its ends to said plate and concentric with said hub, said support positioned at the inner side of said panel, a resistance wire mounted upon said support and having one end electrically connected with the hub, the opposite end of said resistance wire being insulated from the hub and adapted to have a lead wire connected thereto, a blade on said hub opposite the point at which the handle is secured and in contact with the resistance wire, said hub adapted to be rotated and carry said blade and move the same along the resistance wire to bring more or less of the wire into the circuit, and said hub having its edge calibrated to indicate the resistance offered by the wire when the hub is in predetermined position.

In testimony whereof I affix my signature in presence of two witnesses.

HERMAN W. TOMPKINS.

Witnesses:

EDWARD J. GILMORE,
N. A. MYERS.
